M. H. Blakeman

ATTORNEY.

UNITED STATES PATENT OFFICE

126,774

DESIGN FOR A HOOD OR SIMILAR ARTICLE

Marion H. Blakeman, Provincetown, Mass.

Application February 18, 1941, Serial No. 99,082

Term of patent 3½ years

To all whom it may concern:

Be it known that I, Marion H. Blakeman, a citizen of the United States of America, residing in Provincetown, county of Barnstable, and State of Massachusetts, have invented a new, original, and ornamental Design for a Hood or Similiar Article, of which the following is a specification, reference being had to the accompanying drawing, forming part thereof.

Fig. 1 is a front view of a hood or similar article showing my new design.

Fig. 2 is a rear view thereof.

Fig. 3 is a plan view of the hood in open position.

I claim:

The ornamental design for a hood or similar article, as shown.

MARION H. BLAKEMAN.
